United States Patent Office

Des. 210,502
Patented Mar. 12, 1968

210,502

MOVIE CAMERA

Dale R. Caldwell, Chicago, Ill., assignor to Argus Incorporated, Chicago, Ill., a corporation of Illinois

Filed May 2, 1966, Ser. No. 2,083

Term of patent 14 years

(Cl. D61—1)

FIG. 1 is a front perspective view from one side of the movie camera showing my new design;

FIG. 2 is a front perspective view of the other side of the camera;

FIG. 3 is a bottom view thereof; and
FIG. 4 is a rear view thereof.

I claim:

The ornamental design for a movie camera, substantially as shown.
